(57) **CLAIM**

The ornamental design for an eyeglass cleaner, as shown and described.

DESCRIPTION

FIG. 1 is a front perspective view of an eyeglass cleaner showing my new design, the broken line showing of a partial eyeglass is for illustrative purposes only and forms no part of the claimed design;

FIG. 2 is a left side elevational view, the right side elevational view being a mirror image thereof;

FIG. 3 is a front end elevational view;

FIG. 4 is a top view, the bottom view being a mirror image thereof; and,

FIG. 5 is a rear end elevational view.
